improved, including full科教, information and a description of the invention, and of the manner and process of making the same, for patent purposes, in accordance with the patent laws of the United States and of other countries, and of the best mode contemplated by the inventor of carrying out his invention, and now applies for a patent to the United States Patent Office.

UNITED STATES PATENT OFFICE

2,453,834

COMBINATION CORSET AND STOCKING RETAINER

Lola Monica Deegan, Melbourne, Victoria, Australia

Application November 26, 1947, Serial No. 788,171

In Australia January 25, 1946

3 Claims.

(Cl. 2—313)

This invention relates to combination corset and stocking retainer for preventing displacement of such garments when in use and more particularly refers to such retaining devices which are adapted to prevent upward displacement of a corset, girdle or the like when the user is not wearing stockings.

When stockings are worn in the usual way, the suspenders, which are invariably secured to corsets and the like as an integral part of the garment, are detachably connected at their lower ends to the upper ends of the stockings by suitable clips or fasteners, thus supporting the stockings and at the same time holding down the corset or the like against upward movement, for instance, when the wearer is stooping or bending.

An additional disadvantage which arises when corsets and the like are worn without stockings is that the suspenders dangle loosely and uncomfortably about the wearer's leg.

The primary object of the present invention is to provide a simple, inexpensive and efficient device whereby the lower ends of the suspenders attached to a corset or like garment may be anchored so as to prevent the garment from creeping upward out of normal position, for instance, when the wearer is stooping or bending, and whereby the inconvenience and discomfort caused by loosely dangling suspenders when stockings are not worn, is avoided.

A further object of the invention is to provide a device which is also capable of being used when stockings are worn for the purpose of firmly retaining the stockings in position without the suspender fastener deforming the top of the stocking as usual, and causing laddering of the fabric.

Further objects of the invention will become apparent from the following detailed description, reference being had to the accompanying drawing wherein—

Figure 1 is a perspective view of a retainer device in accordance with one embodiment of the present invention;

Figure 2 is a perspective view showing the device in use for holding down corsets or like garments;

Figure 3 is a perspective view showing the device performing the dual function of retaining a corset or like garment and a stocking in the desired position; and

Figure 4 is a perspective view showing the device in use for supporting a stocking without the use of suspenders.

According to the present invention the im-

proved device is in the form of an endless retainer band 2 which is preferably composed of latex but may consist of other suitable natural, or synthetic rubber, moulded plastic or any other suitable elastic material of a sufficiently tough nature to withstand the strain to which the band is likely to be subjected when in use.

The retainer band is adapted to form a close fit upon the wearer's thigh and for this purpose it preferably converges downwardly between the upper and lower marginal edges 3 and 4 respectively, of the band as shown in the drawings.

In order that the retainer band may have an effective frictional grip with the skin of the wearer or with hosiery, the band is of greater width than conventional types of garters. For example the width of the improved retainer band is preferably of the order of from one third to two thirds its diameter, thus providing an enlarged gripping surface on the inside of the band of sufficient area to meet with requirements.

The retainer band is adapted for detachable connection to a plurality of suspenders or the like 6 of the type usually provided on corsets, girdles and like garments. For this purpose the retainer band is preferably provided adjacent to its upper marginal edge with a plurality of circumferentially spaced apertures 7 through which the fasteners 8 on the suspenders may be passed.

These apertures 7 and the upper and lower marginal edge portions of the retainer band are preferably reinforced in any suitable manner such, for example as by beading or the like. Fabric reinforcement is also preferably incorporated in the improved retainer band at or adjacent to the upper edge thereof.

When a retainer band, as aforesaid, is worn without stockings to hold down corsets or the like, the band has a tendency to creep upwardly along the wearer's leg. In addition, when the retainer band is worn without corsets to support hosiery there is a tendency for the band to creep or slide down along the wearer's leg. In order to oppose such undesirable movement of the retainer band when in use, the band is provided on its inner surface with anti-slipping means.

According to the invention as illustrated in Figure 1 said anti-slipping means consists of a series of spaced projections forming an uneven or slightly roughened surface 11 on the inside and over the entire inner wall of the molded retainer band.

As seen in Figure 2 the improved device is particularly suitable for use when hosiery is not worn. In this case the molded retainer band 2,

which is connected to the corset or like suspenders 6, forms a close, neat fit upon the wearer's thigh and effectively opposes undesirable displacement of the corset or like garment, and in addition avoids the discomfort of loosely dangling suspenders.

If desired, the improved molded retainer band may perform the dual function of holding down a corset or like garment and in addition retaining a stocking 16 in position. Such use is illustrated in Figure 3 from which it will be noted that the improved molded retainer band is positioned so as to overlie the top edge portion of the stocking. An important advantage of this use is that the suspenders are connected to the retainer band instead of to the stocking tops. The stocking is thus relieved of the localized pull of each suspender and the possibility of runs developing in the stocking is reduced to a minimum.

When corsets, girdles, or like garments are not worn, the improved retainer band is adapted for use solely as a support for the hosiery. In this case the molded retainer band is operatively positioned in such a manner that the upper portion of the band grips the skin of the wearer, whilst the lower portion of the band overlies the stocking top and functions to firmly retain it in position as indicated in Figure 4.

Various arrangements, modifications and additions may be incorporated in the foregoing without departing from the scope of the invention as defined by the appended claims.

Having now fully described my invention what I claim is:

1. A combination corset and stocking retainer comprising an endless retainer band composed of a molded elastic material and adapted to form a close fit on the wearer's thigh and which is adapted for connection to a plurality of corset suspenders or the like, said endless band having anti-slipping means formed on its inner surface for opposing creeping of the band along the wearer's leg, said anti-slipping means being comprised of a plurality of spaced projections forming a roughened surface on the inside of said band.

2. A combination corset and stocking retainer comprising an endless retainer band made of a molded elastic material and adapted to form a close fit on the wearer's thigh and having a width of from one third to two thirds its diameter, said band converging downwardly from the upper to the lower marginal edge thereof, said band being provided on its inner surface with anti-slipping means for opposing creeping of the band along the wearer's leg, said anti-slipping means being comprised of a series of spaced projections forming an uneven surface on the inside of the band.

3. A combination corset and stocking retainer comprising an endless retainer band made of a molded elastic material and adapted to form a close fit on the wearer's thigh and which has a width of the order of from one third to two thirds its diameter, said retainer band being provided on its inner surface with anti-slipping means comprised of a series of spaced projections forming an uneven surface on the inside of the band so that when in use part of the band may overlie the top of the stocking in such manner that the upper portion of the band grips the skin of the wearer, while the lower portion grips the stocking top.
